L. DE FOREST

LOUD SPEAKING DEVICE

Filed Oct. 28, 1922

UNITED STATES PATENT OFFICE.

LEE DE FOREST, OF NEW YORK, N. Y., ASSIGNOR, BY MESNE ASSIGNMENTS, TO DE FOREST PHONOFILM CORPORATION, OF JERSEY CITY, NEW JERSEY, A CORPORATION OF DELAWARE.

LOUD-SPEAKING DEVICE.

Application filed October 28, 1922. Serial No. 597,514.

To all whom it may concern:

Be it known that I, LEE DE FOREST, a citizen of the United States, residing at New York, county and State of New York, have made a certain new and useful Invention in Loud-Speaking Devices, of which the following is a specification.

This invention relates to loud speaking devices.

10 An object of the invention is to provide a device of this nature which is simple in construction, economical of manufacture and efficient in operation.

15 A further object of the invention is to provide a loud speaker of this type wherein the ordinary telephone receiver may be employed for the purpose of effecting the amplified or loud reproduction of the electrical variations in telephone receivers.

20 Further objects of the invention will appear more fully hereinafter.

The invention consists substantially in the construction, combination, location and relative arrangement of parts, all as will be 25 more fully hereinafter set forth as shown by the accompanying drawing and finally pointed out in the appended claims.

Referring to the drawing:

Figure 1 is a view in side elevation of the 30 loud speaker construction embodying my invention, the same being shown in longitudinal section.

Fig. 2 is a similar view of a slightly modified construction embodying my invention.

35 Fig. 3 is a sectional view taken on the lines 3—3 of Fig. 2, looking in the direction of the arrow.

The same part is designated by the same reference character wherever it occurs 40 throughout the several views.

There are known to the art loud speaking devices in which the sound is led from its source into a second horn or cone of slightly stretched paper, thin leather or other non-metallic material, for transmitting sound waves. Such horns are being used, for instance, in connection with phonographs in which the phonograph needle is located at the apex of the cone.

50 It is among the special purposes of my present invention to provide a loud speaking device which utilizes this type of diaphragm or cone but which operates on a different principle and therefore is made avail-

able for use in connection with electrical sound receiving apparatus, such as a telephone receiver, and thus provide a device which is adaptable for the reception of all electrical communications such as radio communications or the like.

In accordance with my invention I employ a cone structure consisting essentially of a spider 1 preferably with a comparatively heavy rim, between parts of which is clamped a non-metallic diaphragm 2, such as parchment, paper, thin leather, or the like. This parchment is stretched, preferably in the shape of a cone, but I do not desire to be restricted or limited in this respect. The diaphragm may be maintained in taut 70 position in any suitable manner, for example, by means of a rod 3 terminating at one end in a spider 14 which supports a ring 15 secured thereto, said ring to engage the diaphragm preferably one-half or one-third 75 of the distance from the apex of the cone to the periphery. The rod 3 is provided with screw threads 5 at the opposite end thereof which engage a nut 6 positioned inside of the hub of the spider 1.

It will thus be seen that by varying the position of the nut which is on the threaded portion 5 of the rod 3, the tension imparted to the diaphragm 2 may be varied, thus permitting an easy manner of maintaining the 85 diaphragm taut under all conditions of temperature or atmospheric conditions.

The apex of the conical diaphragm is provided with a needle point 7 projecting through the diaphragm 2 and this needle 90 point is placed in contact with the diaphragm of an ordinary telephone receiver. Thus it will be seen that the vibrations imparted to the diaphragm of the ordinary telephone receiver 8 are imparted directly to 95 the diaphragm 2, and thus the sound in a greatly amplified condition is reproduced in an undistorted non-metallic manner, the shape of the diaphragm tending to concentrate the sound waves in a most efficient 100 manner.

It will be apparent that it is immaterial whether the telephone receiver 8 is located outside of the cone, as shown in Fig. 1, or on the inside of the cone, as shown in Fig. 105 2. In the latter arrangement the telephone receiver 8 is supported by the hub of the web 1 in any suitable manner, for example,

- by means of the brackets, as diagrammatically illustrated. In this instance the rod 3, remote from the apex of the cone, is placed in needle contact with the diaphragm 5 of the telephone receiver 8, and the rod 3 is maintained taut by means of a suitable spring 9 secured at one end to the rod 3, and at the other end to the supporting wall or structure 10.
- 10 For the purpose of providing a simple and efficient supporting structure for the loud speaking device of my invention, I have shown an arrangement in Fig. 1 wherein the device is attached to any suitable supporting body, such as a wooden strip illustrated at 10. This base 10 is provided with a suitable bracket 11 for supporting the telephone receiver. Rigidly secured to the wooden base strip is an arm 12, the end of 15 which is pivotally clamped in any suitable manner to the lower portion of the rim 1. A spring 13 is detachably secured at one end to the upper portion of the rim 1, and at the other end permanently affixed to the base 20 strip 10 as shown. The function of the spring 13 is to maintain the arm 3 in firm contact with the diaphragm of the telephone receiver 8. I have found that if the wooden base 10 be made part of, or attached directly to, one side of a hollow sound-resonant chamber or box having one side open, or having suitable apertures cut into one of its sides, e. g., a violin or violin-cello body, then the acoustic effect produced 25 by the vibration of the conical diaphragm is greatly enhanced. I prefer, therefore, to employ the arrangement herein described mounted upon such hollow resonant chamber, as shown at 20.
- 30 Many modifications and changes in detail will readily occur to those skilled in the art without departing from the spirit and scope of my invention, but having now set forth the objects and nature of my invention, and having shown and described a construction embodying the principles therein, what I claim as new and useful and of my own invention, and desire to secure by Letters Patent is:
- 35 1. A loud speaking device, comprising in combination with a telephone receiver of the diaphragm type, a substantially cone-shaped body of non-metallic material, and means for vibrating said body by and in accordance with the vibrations of the diaphragm of said telephone receiver.
- 40 2. A loud speaking device, comprising in combination with a telephone receiver of the diaphragm type, a substantially cone-shaped body of non-metallic material, and a rigid member extending from the apex of said body and contacting with the surface of the diaphragm of said telephone receiver. 60
- 45 3. A loud speaking device, comprising in combination with a telephone receiver of the diaphragm type, a substantially cone-shaped body of non-metallic material, means for adjustably maintaining said body in a taut condition, and means for vibrating said body by and in accordance with the vibrations of the diaphragm of said telephone receiver. 65
- 50 4. A loud speaking device, comprising in combination with a telephone receiver of the diaphragm type, a substantially cone-shaped body of non-metallic material, means for adjustably maintaining said body in a taut condition, said means including means for vibrating said body by and in accordance with the vibrations of the diaphragm 70 of said telephone receiver. 75
- 55 5. In a loud speaking device, a case, a telephone receiver supported therein, a substantially cone-shaped body of non-metallic material provided with a substantially rigid extension from the apex thereof, and means for supporting said body in said case so that the end of said extension is in contact with the surface of the diaphragm of said telephone receiver. 80 90
- 60 6. In a loud speaking device, a case, a telephone receiver supported therein, a substantially cone-shaped body of non-metallic material provided with a substantially rigid extension from the apex thereof, and means for detachably supporting said body in said case so that the end of said extension is in contact with the surface of the diaphragm of said telephone receiver. 95
- 65 7. In a loud speaking device, a case, a telephone receiver supported therein, a substantially cone-shaped body of non-metallic material provided with a pin attached to the apex thereof, and means for supporting said body so that the end of said extension is in contact with the surface of the diaphragm of said telephone receiver. 100 105
- In testimony whereof I have hereunto set my hand on this 15th day of October A. D., 1922.

LEE DE FOREST.
